(57) **CLAIM**

The ornamental design for a hand-held scrubbing tool, as shown and described.

DESCRIPTION

FIG. 1 is a perspective view from above showing my design for a hand-held scrubbing tool;

FIG. 2 is a top plan view thereof; and,

FIG. 3 is a front elevation view thereof, the remaining elevation views being identical.

The broken lines depict portions of the hand-held scrubbing tool that form no part of the claimed design.
